UNITED STATES PATENT OFFICE.

HERMAN IHLENBURG, OF PHILADELPHIA, PENNSYLVANIA, ASSIGNOR TO THE
MACKELLAR, SMITHS & JORDAN COMPANY, OF SAME PLACE.

DESIGN FOR A FONT OF PRINTING-TYPE.

SPECIFICATION forming part of Design No. 22,019, dated November 29, 1892.

Application filed October 28, 1892. Serial No. 450,288. Term of patent 7 years.

To all whom it may concern:

Be it known that I, HERMAN IHLENBURG, a citizen of the United States, and a resident of Philadelphia, Pennsylvania, have invented a new and original Design for a Font of Printing-Type, of which the following is a specification.

My design for a font of printing-type is clearly illustrated in the accompanying typographical impression.

The general feature of the design is the light appearance of the characters, which are, however, heavy-faced.

The font consists of the upper and lower-case letters and the Arabic numerals. The lower-case and numerals are in keeping with the upper-case characters. All the main lines of the characters are tapered and solid. The lines of the letter "A" are curved as well as tapered, and the left-hand line of the letter "H" is also curved, terminating in a scroll, and

the right-hand line of the letter "M" is curved, and extending from the right-hand lower corner of each of the letters "A," "C," "K," "M," "N," "Q," and "R" are curved lines. The horizontal limb of the letter "L" is also extended in keeping with the above letters. The lines of the letters "V," "W," and "Y" are curved as well as tapered, and the letters "F," "G," "I," "J," "Q," "S," and "T" are 30 ornamented by short scrolls.

I claim—

The design for a font of type, substantially as described, and shown in the accompanying typographical impression.

In testimony whereof I have signed my name to this specification in the presence of two subscribing witnesses.

35 HERMAN IHLENBURG.
